UNITED STATES PATENT OFFICE.

GUIDO PITONI, OF ROCHESTER, NEW YORK.

SOUNDING-TOY WHEEL.

1,384,334.

Specification of Letters Patent. Patented July 12, 1921.

Application filed May 29, 1920. Serial No. 385,253.

To all whom it may concern:

Be it known that I, Guido Pitoni, subject of King of Italy, residing at Rochester, in the county of Monroe and State of New York, have invented new and useful Improvements in Sounding-Toy Wheels, of which the following is a specification.

This invention relates to toys and aims to provide a novel form of musical wheel 10 which may be rotated to produce pleasing sounds or notes.

Another object is the provision of novel means whereby the wheel may be rotated so that a child or other person may walk 15 or run, causing the sound device to operate.

Another object is the provision of means for protecting the sound device from injury in the event of the wheel falling upon either side.

20 With the above and other objects in view, the invention includes the following novel features and details of construction, to be hereinafter more fully described, illustrated in the accompanying drawings and pointed 25 out in the appended claims.

In the drawings:—

Figure 1 is an elevation of the wheel.

Fig. 2 is a vertical sectional view of the same.

30 Referring specifically to the drawings, wherein like characters of reference denote corresponding parts, the wheel comprises a disk 10 which is made of wood or other suitable material and is provided with a central opening 11. Extending through this opening is a pin 12 which is provided at one end with an eye 13 and at its opposite end with a member 14 by means of which the pin is swiveled within the opening. Secured to the eye 13 is a chain or other flexible element 15 which carries at one end a handle 16. By this means the wheel may be rotated, the handle being firmly held, while the holder may walk or run, whereupon the 45 wheel will be rolled along the sidewalk or floor.

Secured to the disk 10 and surrounding the opening 11 is a cup shaped member 17 and extending from beneath this member 50 and secured to the disk 11 is a plurality of sound tubes 18. These tubes are provided with openings 19 and have their outer open ends located in juxtaposition to gongs 20 carried by the disk 10. If desired these 55 gongs may be of different tone so that when sounded in a manner hereinafter explained,

will produce different notes. The gongs are sounded during the rotation of the wheel by means of metallic balls 21 or similar devices which are retained within the grooves 60 18 and are movable therein by gravity as the wheel is rotated so that the gongs 20 will be consecutively sounded.

In addition, the wheel is provided with other sound devices in the form of bells 22 65 which are secured to the disk, these bells being also sounded during the rotation of the wheel.

In order to protect the sound device from injury in the event of the wheel falling upon 70 its face and to provide a rim upon which the wheel will travel, the disk 10 is surrounded by an annular metallic flange 23 which extends above the height of the sound devices so as to provide their contact with the floor 75 or sidewalk and provides an open top receptacle within which all of the sound devices are located.

The invention is susceptible of various changes in its form, proportions and minor 80 details of construction and the right is herein reserved to make such changes as properly fall within the scope of the appended claims.

Having described the invention what is 85 claimed is:—

1. A toy embodying a wheel formed of a disk, a relatively wide protecting flange surrounding the disk, a plurality of radially arranged sound tubes carried by the disk, 90 a gong located at the outer end of each of the tubes, balls operating within the tubes for contact with the gongs when the wheel is rotated and a flexible element centrally connected to the wheel. 95

2. A toy comprising a wheel, a plurality of radially arranged tubes carried by the wheel, a sound element located at the outer ends of each of the tubes and movable elements within the tubes and adapted to contact with the sound element when the wheel is rotated. 100

3. A toy comprising a wheel, a plurality of radially arranged perforated tubes carried thereby, a plurality of circumferentially arranged gongs located at the outer ends of the tubes, gravity controlled elements operating within the tubes for contact with the gongs when the wheel is rotated. 105

In testimony whereof I affix my signature. 110

GUIDO PITONI.
